UNITED STATES PATENT OFFICE

1,982,270

SUPPORTING MEANS FOR CAR DOORS

Kenneth J. Tobin, Chicago, Ill., assignor to
 Camel Company, Chicago, Ill., a corporation of
 Illinois

Application December 17, 1931, Serial No. 581,554

7 Claims. (Cl. 20—22)

This invention relates to supporting means for car doors and more particularly to a structure embodying ball bearing elements which are confined upon the inside surface of the door and the arrangement is such that the weather will be effectively excluded from entering between the door and the floor of the car. In connection with the advantages resulting from such a structure may be mentioned simplicity in design, ready adaptability and cheapness of construction.

A further feature of the invention resides in an automatic latching mechanism for latching the door either in its closed or open position, a feature which is extremely desirable due to the fact that the door is susceptible of such free and easy movement upon its ball bearing mounting.

The invention comprises the novel structure and combination of parts hereinafter described and more particularly pointed out and defined in the appended claims.

In the accompanying drawings which illustrate a preferred form of this invention and in which similar reference numerals refer to similar features in the different views:

Figure 1 is a fragmentary side elevational view of a house car illustrating the application of a side door embodying the present invention.

Figure 2 is an enlarged fragmentary vertical sectional view taken upon the line II—II of

Figure 1 looking in the direction of the arrows and in which the latching mechanism is illustrated in both locking and unlocking positions.

Figure 3 is a fragmentary front elevational view of the lower front corner of the door illustrating more clearly the locking and retaining mechanism.

Figure 4 is a horizontal vertical sectional view taken on the line IV—IV of Figure 3 looking in the direction of the arrows.

Figure 5 is a fragmentary vertical sectional view of a modified form of ball supporting means.

Figure 6 is a fragmentary view of a ball retainer that may be used.

In referring to the drawings, it will be noted that a side sill 1 of a house car has been illustrated as cut away as indicated at 2 in the region of the doorway, and as embodying a Z-bar 3, the lower flange of which forming a track for supporting the car door and being deflected downwardly as indicated at 4 to provide a guide member. A door 5 is adapted to be supported upon the lower flange 3a of said Z-bar. This door has a lower plate member 6 upon its inner surface to which a pair of opposed plate members 7 and 8 are attached. The plate 7 is provided with a lower

outwardly bent portion whereby a shoulder 7a is formed that forms a contacting flange for bearing balls. The plate 8 is provided with an inwardly curved portion, the outer edge 8a of which forms a contact flange for the bearing 60 balls.

A freely floating ball spacing element 9 of angular formation having a flange 9a riding upon the curved portion of the plate 8 is provided. This ball spacing element is provided with suitably formed spurs 10 for receiving the ball bearing elements 11 therebetween. It will be noted that the ball bearing elements 11 contact the points 7a, 8a, and the track 3a thereby forming a three point support whereby there will be very 70 little if any slippage of the balls during their traveling movement. The lower edge of the door is provided with suitable guide brackets 12 which receive the guide portion 4 of the door as shown in Figure 2. Each guide bracket 12 is secured 75 by rivets 13 which may be readily removed when it is desired to dismount the door.

It will be observed that the lower portion of the door is normally maintained adjacent the track 3a with the result that the weather is 80 largely excluded from entering the car at the lower margin of said door. It will further be appreciated that the bearing balls 11 are securely housed against exposure to the weather.

In the modified form as shown in Figure 5, 85 the door which is designated by the reference 5a has a pair of plates 14 and 15 attached to the lower plate 6. The plate 14 is provided with a horizontal flange 14a that rests directly upon the bearing balls 11 directly opposite the point 90 of engagement of such balls with the track 3a whereby a two point bearing is provided. The plate 15 is outwardly offset and serves as a retaining member. In this modified construction any suitable form of ball spacer 16 may be provided for maintaining the balls in proper spaced relation. In instances where the matter of slipping of the balls upon the track is of little consequence, it may be desirable to employ the structure shown in Figure 5 which can be very cheaply and readily manufactured. It will be evident from an inspection of Figure 5 that the weather is effectually excluded from entering between the car and the lower portion of the door. It will also be apparent that the balls in this modified 105 construction are also securely housed against exposure to the weathering elements.

Due to the fact that a ball bearing door is extremely mobile, it is desirable to provide mechanism for automatically latching the same in its 110

open or closed position. To this end a latch lever 17 is pivoted upon a bracket 18 upon the lower front portion of the door as indicated at 19. The lower end of the latch lever 17 has an 5 inwardly directed arm 20 which is adapted to engage a recess 21 in a latch plate 22 as shown in Figure 4. Such a latch plate is provided at spaced points upon the car for latching the door in its closed position and for also latching the 10 door in its open position. With reference to Figure 4 it will be observed that the latch plates 22 are provided with inclined walls 23 which extend from the side of the car to the outer edge of the groove so that the lever in its movement 15 with the door may ride outwardly upon the sloping or cam portions 23 and drop by gravity into the groove 21 to securely latch the door against movement until the latch lever is withdrawn from such groove.

20 It is desirable in transit to lock the latch lever 17 against unauthorized operation and to this end there is provided a locking lever 24 which is pivoted to the door as indicated at 25 and is provided with a socket 26 at its free end for 25 engaging the upper end of the lever 17. The lever and walls of the socket 26 are provided with suitable slots or apertures 27 for receiving a sealing ribbon whereby the lever 17 may be sealed in its closed position when the car door 30 is closed and ready for transit.

An angular threshold plate 28 is preferably attached to the side sill 1 and the outstanding flange of this angle plate is provided with a depending flange 29 against which the door 5 may 35 abut. In addition to forming a threshold plate and strengthening the side sill 1 to compensate for the cut out portion, this plate also serves to exclude the weather from entering the car when the door is in its closed position.

40 The car is provided with upper and lower stop members 30 as shown in Figure 1 which are adapted to be engaged by the car door at a predetermined distance from the door opening in order to stop the movement of the door at the 45 proper time for the engagement of the latching lever with the latch plate 22. At the front edge of the door opening, there is a weatherstrip 31 that cooperates with suitable weatherstrip 32 upon the front edge of the door for limiting or 50 stopping the closing movements of the door when in position to allow the latch lever to engage the locking groove in latch plate 22.

55 It will be appreciated that the ball bearing mounting for the car door involving this invention is wholly upon the inside surface of the door and is securely housed against exposure to the weather and forms at the same time an efficient weather sealing means for the lower portion of the door.

60 I am aware that many changes may be made and numerous details of construction may be varied through a wide range without departing from the principles of this invention, and I therefore do not purpose limiting the patent granted 65 hereon otherwise than necessitated by the prior art.

I claim as my invention:

1. In a house car having a floor and a side with a doorway, an angle member upon the bottom of the floor and embracing the edge thereof, said member being cut away at said doorway, a threshold plate secured to said member at said

doorway, said member having a horizontal track below said doorway, a door mounted upon said car for closing said doorway, and rolling means between the inner side of said door and said track.

2. In a house car having a door opening, a door for closing said opening, a track depending from said car, a raceway upon the inner side of said door, bearing balls mounted between said track and raceway and a freely floating spacing element for said balls having a flange slidably supported upon said raceway.

3. In a house car having a floor and a side with a door opening, a threshold plate secured to the edge of the floor adjacent said door opening, a track member secured to the bottom of the floor and having a horizontal flange extending in parallel relation to said threshold plate, said flange having a downwardly bent lip, a door for closing said opening, a raceway upon the inner side of said door, bearing balls between said track and raceway and guide clips upon the lower edge of said door for engaging behind said lip for guiding said door, said door cooperating with said threshold plate to exclude the weather.

4. In a house car having a door opening, a member upon the lower part of the car comprising a vertical portion and a horizontal track portion, a door for closing said opening, a ball raceway attached to the lower interior portion of the 105 door, bearing balls between said track portion and raceway, and a spacing element for said balls guided between said raceway and said vertical portion of said member.

5. In a house car having a floor and a side with 110 a door opening, an angle member secured to the bottom of said floor and embracing the edge thereof, a depending track member on said angle member, said track member comprising a vertical portion and a horizontal track portion with a de- 115 pending lip, a door for closing said opening, a raceway upon the interior side of said door, bearing balls between said raceway and track portion, a spacing element for said balls guided between said raceway and vertical portion and guide 120 brackets upon the lower edge of the door co-operating with said lip.

6. In a house car having a floor with an edge, an angle member embracing the bottom of the floor and said edge and extending thereabove, 125 said member being cut away at the doorway, an angular member secured to the side of said member in substantial alinement with the top of the floor, said angle member having a door supporting track secured thereto, a door having an in- 130 terior ball raceway, balls mounted between said track and raceway, said door cooperating with said track and angular member to exclude the weather.

7. In a house car having a floor and a side 135 sill embracing the bottom of the floor and ex-tending thereabove, said car having a door open-ing, and said sill being cut away in the region of said opening, a threshold plate attached to the side of the car in alinement with said floor and 140 projecting therebeyond, said side sill having a track thereon, a door for closing said opening, a track upon the interior side of said door and roll-ing elements mounted between said tracks for supporting said door, said door cooperating with 145 said threshold plate to exclude the weather.

KENNETH J. TOBIN.
